UNITED STATES PATENT OFFICE.

ELLIS J. G. PHILLIPS, OF AURORA, ILLINOIS, ASSIGNOR TO RICHARDS-WILCOX MANUFACTURING COMPANY, OF AURORA, ILLINOIS, A CORPORATION OF ILLINOIS.

OVERHEAD-TROLLEY BRACKET AND END CLOSURE THEREFOR.

1,318,691.

Specification of Letters Patent.

Patented Oct. 14, 1919.

Application filed February 10, 1919. Serial No. 276,216.

To all whom it may concern:

Be it known that I, ELLIS J. G. PHILLIPS, a citizen of the United States, and a resident of Aurora, in the county of Kane and State of Illinois, have invented certain new and useful Improvements in Overhead-Trolley Brackets and End Closures Therefor, of which the following is a specification, reference being had to the accompanying drawings.

This invention relates to improvements in supporting brackets for overhead trolley-tracks for sliding doors and the like, and more particularly to an improved blind or stop to be located at one end of each end bracket. As heretofore constructed the outer end of each of such brackets has generally been provided with pieces of sheet metal bent to fit within the bracket and serving as a closure or partial closure therefor, such pieces acting as stops for the wheels of the end trolleys to abut against, but such pieces had no direct connection with the supporting framework to which the brackets themselves were secured and the manner of connecting them to the brackets has not been of a character to afford additional strength to the brackets so as to prevent them from spreading under severe blows or shocks due to the wheels striking such pieces when the doors are moved back with force from closed position.

The principal object of my invention is to provide an improved end closing device for such track-brackets which may be secured not only to the bracket but may also be secured to the framework to which the bracket itself is attached, and by reason of such connections will act as an effective stop for the trolley wheels to abut against, and will also securely hold the bracket against spreading apart or becoming distorted. It is further an object of the invention to so construct such bracket closing members that two of them may be secured together and to the doorway framing at a point over the center of the doorway and serve as an effective stop for the meeting edges of the two doors that are used to close such doorway. These objects I accomplish as illustrated in the accompanying drawings and hereinafter particularly described. That which I be-

lieve to be new will be set forth in the claims.

In the drawings:—

Figure 1 is a view in front elevation of an overhead trolley-track supported in position by brackets, the two end brackets having combined therewith my novel stops or blinds, and two of such stops or blinds being shown in position for the doors shown in the figure to abut against when they are in fully closed position;

Fig. 2 is an enlarged perspective view of the bracket shown at the left hand side of Fig. 1 with my improved stop or blind in place therein;

Fig. 3 is a perspective view of two of the stops or blinds secured together to constitute an abutment for the edges of the doors when such doors are in closed position, as in Fig. 1; and

Fig. 4 is a view similar to Fig. 2, but showing a modified form of stop or blind that is adapted to be used with either of the end brackets, so as to avoid having to make right-hand and left-hand constructions as is the case with the devices shown in the other figures.

Referring to the figures of the drawings,— Fig. 5 indicates a section of overhead trolley-track of well known form which is made of a single piece of sheet metal bent upon itself and having its marginal portions inwardly turned toward each other to form rails upon which run the wheels of door-supporting carriages, as indicated by dotted lines in Fig. 1. From the wheeled carriages referred to, two doors 7—8 are shown suspended, as usual. The brackets that support the track are indicated by 6, and with the exception of two oblong openings shown in the front wall of each bracket, and hereinafter referred to more particularly, these brackets are of ordinary construction. As shown, each comprises a rear member and a front member riveted together, the front member being bent so as to extend over the top of the track and down against its front wall, and the lower marginal portions of the two parts of the bracket being inturned to project under and support the rail members of the track. 9 indicates the main or body portion of one of my improved stops or

blinds, each of the end brackets being equipped with one of such devices. Each stop or blind is formed of a piece of sheet metal, whose main or body portion 9 is of a size and shape to approximate the shape of the interior of a bracket so as to substantially close the outer end thereof. The sheet forming this member is bent to form a vertical stiffening flange 10 which lies parallel with 10 and close to the rear member of the bracket, and when the device is in place the edge of such flange will, as shown in Fig. 2, be substantially flush with the outer edge of the bracket. From such flange projects a wide 15 ear 11 that is off-set, as indicated at 12, sufficiently to bring the rear face of the ear substantially in line with the rear face of the bracket, and thus permit such ear to rest snugly against the supporting framework 20 to which the track-brackets 6 are secured. The ear is provided with an opening 13 that permits of the passage of a screw or bolt so as to secure the stop or blind as a whole firmly to the framework. From the front 25 edge of the member 9, and a short distance above its lower edge, projects a tongue 14 which, at a short distance from the base of the tongue, is bent laterally so that thereby is given to it an approximate hook shape. 30 This hook shaped tongue 14 passes through an opening 15 in the front wall of the bracket 6, as best shown in Fig. 2. The bent or hook-shaped tongue 14, is, of course, to be inserted in its opening 15 before the 35 ear 11 is screwed or bolted to the framework, and it can be so inserted easily by holding the stop or blind in an inclind position within the track, after which, upon moving the bracket into the position shown 40 in Fig. 2, and securing the ear to the framework, the stop or blind will be securely held connected with the bracket, as will be understood. Securing the stop or blind in this manner to the bracket and also to the 45 framework insures the provision not only of an unyielding abutment for the trolley wheels to strike against, but insures the bracket itself being so braced that it is not liable to be moved upon the single securing 50 bolt that passes through the bolt hole *a*, and also insures against such distortion of the bracket itself that sometimes occurs when the doors are moved open with great violence. Such violent opening of the doors with the 55 accompanying shock of the wheels against the ordinary stops will sometimes cause a spreading apart of the two members that constitute the bracket, but by my improved construction and arrangement such spreading apart of the two members is almost impossible to effect, no matter how violently the doors are pushed open.

I have shown each of the brackets—the in-

termediate brackets as well as the end brackets—provided with two of the openings 15, 65 and I prefer to so construct them, notwithstanding the fact that one of such openings in each of the end brackets, and both of the openings in the intermediate brackets, are not made use of, but by having them all 70 constructed alike in this manner, any one bracket may serve as the bracket for either end, and the fact that the intermediate brackets have such openings does not in the slightest degree lessen their value as such intermediate brackets. In short, by having all 75 of the brackets provided with two openings, an order for the required number of brackets for a particular job can be filled from the same stock of brackets, and hence 80 there is no liability of confusion arising in sorting out brackets, particularly those intended for ends from those intended for intermediates, and furthermore, no mistakes 85 can arise on the part of the constructor inasmuch as any one bracket is useful wherever applied.

While the brackets, each provided with the two openings 15, are adapted for use in any situation, yet it is evident that the 90 blinds or stops, as described, must be made in rights and lefts, although, as shown in Fig. 4, it is perfectly feasible to so construct them that the same blind or stop may be used with either end brackets. I accomplish 95 this by making the ear that attaches to the framework of the full width of the narrow flange that rests against the inner face of the rear member of the bracket, and providing the screw or bolt hole in such ear 100 centrally of the width thereof, and by having the turned tongue that engages the front wall of the bracket formed so as to project from the center of the edge of the stop or blind, such ear entering one of two openings 105 formed midway between the top and bottom of the front wall of the bracket. By so changing the construction, the same stop or blind can be used on either end bracket, as will be readily appreciated. In 110 Fig. 4, the same reference numerals are employed as in the other figures, but with the addition of the letter *a* thereto.

The stops or blinds described in connection with Figs. 1 and 2 are also of peculiar 115 advantage in forming, when two of them are secured together and the two secured centrally over the door-way, an abutment for the inner edges of the sliding doors to come in contact with to prevent either door 120 from being moved past the center line of the door-way. By reference to Fig. 2, it will be seen that through the main or body portion 9 of the stop or blind is formed an opening 16. Now, by placing two of these 125 stops or blinds together, as shown in Fig. 3,

with such openings 16 in alinement, and securing them together by a bolt or rivet passed through such openings, a device is formed that can be securely affixed to the 5 frame-work over the door-way by means of screws or bolts passing through the holes 13 in the oppositely-extending tongues 11. Such construction and arrangement permit the lower half of the device thus formed to 10 extend down into the path of the doors, and the two parts thus combined furnish a very strong stop or abutment for the inner edges of the doors to come in contact with, and in thus forming such door stop, no 15 change whatever has to be made in the construction of the united members, or anything done after they have been secured together other than to bolt or screw them in place above the door-way. Indeed, by 20 merely placing them together, and without fastening them by a bolt through the holes 16, they will act as an efficient door stop. As shown in Fig. 1, the part 17 indicates a strip secured to one of the doors and de- 25 signed to cover the crack that would be left between the doors when both of them are moved inwardly against the stop, but such strip might be omitted and, if desired, the edges of the doors near their upper ends be 30 slightly notched so as to properly receive the depending portions of the stop and allow the edges of the doors to contact with each other.

It is because of the adaptability of the 35 bracket stops to the performance of this additional function of stopping the doors that I prefer to make the stops or blinds as rights and lefts, as shown in Fig. 2, rather than making them as shown in Fig. 4, for, 40 in the first described construction, they lend themselves better when united face to face, as described, to this additional function than do the devices shown in connection with the bracket of Fig. 4, although 45 under some conditions of use the latter construction could also be made use of as a center stop for the doors, but as I do not contemplate so using the modified construction, I have not shown the stop or blind 50 therein provided with the hole 16, as in Fig. 2.

What I claim as my invention and desire to secure by Letters Patent, is:—

1. The combination with a trolley-track 55 bracket having front and rear walls spaced a distance apart and in the front wall of which is an opening, of a stop located inside of said bracket, said stop having a tongue projecting from its front edge and 60 entering said opening in the front wall of the bracket and having a turned portion to form a stiffening flange that rests against the rear wall of the bracket and from which

flange extends an attaching ear for attachment to a fixed support.

2. The combination with a trolley-track bracket having front and rear walls spaced a distance apart and in the front wall of which is an opening, of a stop located inside of said bracket, said stop having a forwardly-projecting tongue for engaging said opening and having a laterally-extending ear for attachment to a fixed support, said ear having an offset bend to cause its rear face to lie substantially flush with the rear 75 face of the bracket.

3. The combination with a trolley-track bracket having front and rear walls spaced a distance apart and having an opening in its front wall, of a stop located within the 80 bracket and having lateral extensions from its front and rear margins, respectively, the front marginal extension passing through an opening in the front wall of the bracket with its outer end turned toward the outer 85 end of the bracket and the rear marginal extension turned in the same direction but extending beyond the bracket to form a means of attachment to a fixed support.

4. The combination with a trolley-track 90 bracket having front and rear walls spaced a distance apart and having an opening in its front wall, of a stop located within the bracket and having lateral extensions from its front and rear margins, respectively, the 95 front marginal extension passing through an opening in the front wall of the bracket with its outer end turned toward the outer end of the bracket and the rear marginal extension turned in the same direction but 100 extending beyond the bracket to form a means of attachment to a fixed support, said rear marginal extension being provided with an offset bend to permit the portion lying beyond the end of the bracket to lie substantially flush with the rear face of the bracket.

5. A stop for use in connection with overhead trolley-tracks comprising a body portion adapted to extend between the front and rear walls of a track-bracket and having means at its front edge for detachably engaging the front wall of a bracket and having at its rear portion an integral laterally-turned member adapted to rest for a portion of its width against the rear wall of 115 such bracket and having an offset bend to cause the portion beyond the end of the bracket to lie substantially flush with the rear face of the bracket.

6. A device for use in connection with 120 overhead trolley-tracks, said device comprising a body portion having a lateral projection from its front and rear margins, respectively, said projections both extending in the same direction, one such projection 125 adapted for engaging the front wall of a

track bracket by passing through an opening therein and the other adapted to project beyond the end of the bracket for attachment to a fixed support, said device having
5 an opening through its body portion for alinement with a similar opening in another similar device when such two devices are

placed against each other with their respective projections extending in opposite directions, whereby a fastening device may be 10 passed through said openings to secure the two devices together to form a stop for the inner edges of two sliding doors.
